(57) CLAIM

The ornamental design for a boot, as shown and described.

DESCRIPTION

FIG. 1 is a first perspective view of a boot showing my new design;

FIG. 2 is a second perspective view thereof;

FIG. 3 is a left side view thereof;

FIG. 4 is a right side thereof;

FIG. 5 is a front view thereof;

FIG. 6 is a rear view thereof;

FIG. 7 is a top view thereof; and,

FIG. 8 is a bottom view thereof.

The broken lines and the area within the broken lines shown in the drawings depict portions of the boot that form no part of the claimed design.

1 Claim, 8 Drawing Sheets
